UNITED STATES PATENT OFFICE.

NOAH H. GILLETTE, OF CORTLAND, NEW YORK.

DESIGN FOR A FLAG.

52,789.

Specification for Design.

Patented Dec. 24, 1918.

Application filed March 18, 1918. Serial No. 223,246. Term of patent 7 years.

To all whom it may concern:

Be it known that I, NOAH HORACE GILLETTE, a citizen of the United States, residing at Cortland, in the county of Cortland and State of New York, have invented a new, original, and ornamental Design for Flags, of which the following is a specification, reference being had to the accompanying drawing, forming part thereof.

The figure is a plan view of a flag showing my new design.

It is not desired to limit the design to the exact colors indicated on the drawing except as representing a dark field bearing stars and slightly converging stripes of contrasting colors.

I claim:

The ornamental design for a flag as shown.

NOAH H. GILLETTE.
